(57) **CLAIM**

I claim the ornamental design for a wall switch, as shown and described.

DESCRIPTION

FIG. 1 is a front perspective view of a wall switch showing our new design;

FIG. 2 is a rear perspective view thereof;

FIG. 3 is a front elevation view thereof;

FIG. 4 is a rear elevation view thereof;

FIG. 5 is a top plan view thereof, the bottom plan view being identical thereto; and,

FIG. 6 is a left side elevation view thereof, the right side elevation view being a mirror image thereto.

The broken lines are for illustrative purposes only and form no part of the claimed design.
